UNITED STATES PATENT OFFICE.

ED ELLIS, OF GUTHRIE, OKLAHOMA, ASSIGNOR OF ONE-HALF TO ALPHEUS AMON LEER, OF GUTHRIE, OKLAHOMA.

DOOR-SECURER.

1,086,036.

Specification of Letters Patent. Patented Feb. 3, 1914.

Application filed June 3, 1913. Serial No. 771,501.

To all whom it may concern:

Be it known that I, Ed Ellis, a citizen of the United States, residing at Guthrie, in the county of Logan and State of Oklahoma, have invented certain new and useful improvements in Door-Securers; and I do hereby declare the following to be a full, clear, and exact description of the invention, such as will enable others skilled in the art 10 to which it appertains to make and use the same.

This invention relates to new and useful improvements in door securers, and has for its object to provide a device which may be 15 easily carried about in the user's pocket without in any way endangering either the pocket or the person of the user.

Another object of my invention is to provide a device which may be easily and 20 quickly applied to a door and which will prevent opening of the same without first removing the securer from its locked position.

A still further object of my invention is 25 to provide a guard for the securer which will prevent the points from becoming dull or broken.

With the above and other objects in view, I will now proceed to describe my invention 30 in the following specification and accompanying drawings, in which,

Figure 1 is a perspective view of my improved door securer in its extended position; Fig. 2 is a top plan view; and Fig. 3 is a 35 detail view showing my improved door securer as it would appear when applied.

Referring to the drawings by characters of reference, 1 indicates generally the main body portion of my door securer to which 40 is pivotally connected the frame engaging member indicated generally by the numeral 2. This frame engaging member preferably comprises the wires 3 and 4, having formed at one extremity thereof the loops 45 5. These loops 5 are preferably secured to the bar 6, which is slidably mounted in the body portion 1, as will be more fully herein-after set forth. A web of metal 7 is provided at one extremity with the upturned 50 teeth 8, and intermediate its ends with the teeth 9, which are preferably stamped from a sheet of material and adapted to enter the door jamb when the device is in place. Suitable beads 10 are formed along the lat-

eral edges of the web 7 and are adapted to 55 surround the wire 4 and thereby hold the web in place on the wires. It will be clearly seen that the wires will be firmly held in spaced relation to each other in a manner described above.

The main body portion 1 preferably comprises the U-shaped members indicated by the numeral 11, which are composed of the two arms 12 and 13 and are adapted to surround the post 6, which slides longitudinally through the slots 14 formed intermediate the arms of the U-shaped member. The ends of the U-shaped member 11, opposite the rounded end are preferably bent inwardly, as clearly illustrated in the drawings, and are adapted to lie adjacent each other. A web of metal 15 is interposed between the two U-shaped members 11 and is provided along its lateral extremities with the beads 16, these beads 16 being adapted to firmly clamp the wires 12 and 13 of the U-shaped members and hold the same firmly in place. This bead 16 is preferably depressed, as clearly illustrated at 17, to more firmly bind the wires and prevent them 80 from becoming accidentally displaced.

It will be clearly seen upon referring to the drawings that the post 6 will form a pivot point around which the frame engaging member 2 is adapted to swing. This post 85 is slidably mounted in the slot 14 formed between the wires 12 and 13 of the main body portion, and it will be clearly seen upon referring to Fig. 2 that the frame engaging member is inserted between the door indicated generally at A and the frame B, with the points 8 and 9 entering the frame. The member 1 is then slid longitudinally along the post 6, and the U-shaped wires 11 will overlie a portion of the door. Should any 95 pressure be applied against the door, the main body portion will rock on the pivot 6 and cause the end opposite the U-shaped wires to abut the door frame and thereby prevent said door from being opened.

While in the foregoing I have shown and described the preferred embodiment of my invention, I wish it to be understood that I may change the specific arrangements of parts without in any way departing from 105 the spirit and scope of my invention.

Having thus fully described my invention what I claim is:

In a door securer, the combination of a body portion comprising U-shaped members, a plate secured intermediate said U-shaped members with a frame engaging member comprising wires having loops formed at one end thereof, a post extending through said loops and fixed therein, a plate, beads formed along the lateral edges thereof, said beads surrounding the wires and

holding the same in spaced relation, and 10 teeth formed integral with said plate.

In testimony whereof I affix my signature in presence of two witnesses.

ED ELLIS.
